UNITED STATES PATENT OFFICE.

GEORGE M. LITTLE, OF PITTSBURGH, PENNSYLVANIA, ASSIGNEE TO WESTINGHOUSE ELECTRIC & MANUFACTURING COMPANY, A CORPORATION OF PENNSYLVANIA.

ELECTRIC RESISTANCE FURNACES.

Application filed February 26, 1921. Serial No. 416,162.

To all whom it may concern:

Be it known that I, GEORGE M. LITTLE, a citizen of the United States, and a resident of Pittsburgh, in the county of Allegheny and State of Pennsylvania, have invented a new and useful Improvement in Electric Resistance Furnaces, of which the following is a specification.

My invention relates to electrically-heated apparatus and particularly to electrical-resistance furnaces.

One of the objects of my invention is to provide a relatively simple and compact form of granular-resistance furnace.

Another object is to provide means for obtaining relatively large areas of contact surface between the contact terminals and the resistor.

Still another object is to provide means for compressing the granular resistor to compensate for its oxidation and burning-away during the operation of the furnace and to provide means for withdrawing the oxidized material and for insertion of new material while the furnace is in operation.

Different types of electrical resistance furnaces embodying granular resistors are known in the art, but more or less trouble has been experienced in making electrical contact between the terminals of the electric supply circuit and the granular resistor material, which usually has a small cross-section in order to provide the necessary high electrical resistance.

In practising my invention, I provide an all-metal container divided into two main parts, to which the terminals of the electric supply may be suitably connected.

Means are provided in the container for restricting the area of cross-section of the resistor at a predetermined portion, to the effect that the heat may be generated at the desired place. A suitable container for the material to be melted, such as a crucible, is located in the container and is surrounded by granular resistance material.

Means are provided for introducing the granular material into the container and for withdrawing it therefrom if it has become damaged in service to such a degree as to preclude its further use as a resistor.

Means are also provided for initially compressing the resistor material in the enclosed container, as well as for permitting further compression of the granular material, being

effected whenever oxidation of some of the material or shrinkage of the fire brick walls or expansion of the outer shell has reduced the pressure inside the container, as indicated by the unsatisfactory operation of the furnace.

Referring to the single sheet of drawings,

Figure 1 is a top plan view of a device embodying my invention, with certain parts cut away, and

Fig. 2 is a view, in cross-section, on the line II—II of Fig. 1.

A metal container 1 comprises a substantially tubular member 2 which is provided with a cover member 3, suitably secured thereto by a plurality of bolts 4.

A bottom plate 5 is secured to the lower flange of the container 2 by means of a plurality of bolts 6, being suitably insulated therefrom by means of an insulating member 7 of substantially annular contour.

Suitable supply-circuit terminals 8 and 9 are secured to the container 2 and the base plate 5, respectively, by means of bolts 10. If desired, an additional metal plate 11, or a plurality of such plates, may be used to increase the effective area of contact between the terminal and a mass of granular electrical-conducting resistor material 12 which is located inside the container 1.

A pier or column 13 is located in the container 1 and is of such dimensions that it supports a crucible 14 in proper operative position in the container 1. The column 13 may consist of a number of layers of fire-brick 15 and a top or facing plate 16 of carborundum or other similar substance adapted to stand the high temperature to which it will be subjected.

A hollow circular pier or column 13, of substantially truncated-cone shape, is provided in the container 1, being built up of fire-brick 15 and a facing 17 of carborundum, alundum, or magnesite. The location and dimension of the member 16 are such as to cause a restriction of the area of cross-section of the granular resistor 12 immediately surrounding the lower part of the crucible 14, thus providing a resistor of relatively high resistance, while, at the same time, having relatively large terminal areas of granular electrical-conducting material.

Openings 18 and 19 are provided in the cover member 3 to permit of the granular resistor material 12 being placed therein.

Similar openings 20 are provided in the bottom plate 5 to permit of withdrawing the oxidized material from the bottom of the furnace and may be closed by suitable plugs 21. Plugs 22 are provided to close each of the openings 18, and relatively long plugs 23 are provided in the openings 19 to permit of compressing the granular resistor material in the container 1, both initially and during the operation of the furnace when this is shown to be necessary by the failure of the furnace to operate properly.

Lifting members 24 may be provided in the top plate 3 to permit of lifting the container 1 by means of a lifting chain 25 for purposes of pouring the melted metal out of the crucible 14.

It may be noted that the device embodying my invention provides a granular resistor having a relatively large area of contact engaging the supply circuit terminals, thus insuring that the material in this part of the electrical circuit will not be consumed by arcing which frequently occurs between the grains of a granular resistor when the same is not tightly packed.

My invention further provides relatively simple means for restricting the area of the path traversed by the current, to a predetermined portion relatively to the crucible.

My invention further provides relatively simple means for effecting initial and subsequent compression of the granular resistor and for permitting the withdrawal and the insertion of granular material while the furnace is in operation.

Various modifications may be made in the device embodying my invention without departing from the spirit and scope thereof, and I desire that only such limitations shall be placed thereon as are imposed by the prior art or are specifically set forth in the appended claims.

I claim as my invention:

1. An electric furnace comprising a metal container, a metal cover for said container, a metal base plate secured to and insulated from said container, means for attaching electric supply-circuit terminals to said container, granular resistor material surrounding said crucible, and means in said cover for compressing said resistor material in said container. 45

2. An electric-resistance furnace comprising a metal base plate, a closed metal container secured to and insulated from said base plate, contact terminals secured to said base plate and said container, respectively, 50

a crucible in said container, a mass of granular resistance material located in said container, means comprising a wall of refractory insulating material surrounding said crucible, but out of contact therewith, for reducing the amount of material adjacent to said crucible, means in said base plate for 55 permitting the withdrawal of said granular resistance material, and means in the top of said container for permitting the introduction of additional resistance material while the furnace is in operation. 70

3. An electric resistance furnace comprising a metal base plate, a closed metal container secured to and insulated from said base plate, contact terminals secured to said base plate and said container, respectively, 75 a crucible in said container, granular resistor material surrounding said crucible, and means in said container for permitting the introduction of granular resistor material into said container and for compressing the same therein, during the operation of the furnace. 80

In testimony whereof, I have hereunto subscribed my name this 10th day of February, 1921.

GEORGE M. LITTLE.
